US00D983187S

(12) **United States Design Patent** (10) Patent No.: **US D983,187 S**
Ma (45) Date of Patent: **** Apr. 11, 2023**

(54) **PROTECTIVE COVER FOR CELLPHONE**

(71) Applicant: **Ruoqiong Ma**, Shantou (CN)

(72) Inventor: **Ruoqiong Ma**, Shantou (CN)

(**) Term: **15 Years**

(21) Appl. No.: **29/768,402**

(22) Filed: **Jan. 29, 2021**

(30) **Foreign Application Priority Data**

Jan. 21, 2021 (CN) 202130044589.6

(57) **CLAIM**

The ornamental design for a protective cover for cellphone, as shown and described.

DESCRIPTION

FIG. 1 is a front perspective view of a protective cover for cellphone showing a kickstand in an open state showing my new design;

FIG. 2 is a rear perspective view of the protective cover for cellphone;

FIG. 3 is a front elevational view of the protective cover for cellphone shown in an alternate configuration with the kickstand in a closed state;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is another perspective view thereof.
